Primary Examiner — Zenia Bennett(74) Attorney, Agent, or Firm — Lando & Anastasi, LLP(57) CLAIM

The ornamental design for a recreational flotation device, as shown and described.

DESCRIPTION

FIG. 1 is a perspective view of a recreational flotation device in accordance with our new design.

FIG. 2 is a top plan view of the recreational flotation device of FIG. 1.

FIG. 3 is a bottom plan view thereof.

FIG. 4 is a front elevational view.

FIG. 5 is a right-side elevational view. The left-side elevational view is a mirror-image thereof; and,

FIG. 6 is a rear elevational view.

The broken lines shown in the drawing are for illustrative purposes only and form no part of the claimed design.
